UNITED STATES PATENT OFFICE.

WILLIAM E. KELLY, OF NEW BRUNSWICK, NEW JERSEY.

HEADER FOR STEAM-BOILERS.

SPECIFICATION forming part of Letters Patent No. 423,932, dated March 25, 1890.

Application filed August 13, 1888. Serial No. 282,613. (No model.)

To all whom it may concern:

Be it known that I, WILLIAM E. KELLY, of New Brunswick, in the county of Middlesex, in the State of New Jersey, have invented 5 a certain new and useful Improvement in Headers for Steam Boilers or Generators, of which the following is a specification.

I will describe a header embodying my improvement in detail, and then point out the 10 various novel features in the claims.

In the accompanying drawings, Figure 1 is a front view of a header embodying my improvement. This header has two covers. One is removed, so that the interior of that 15 portion of the header covered by it may be seen. Fig. 2 is a vertical section taken at the plane of the dotted line $x\ x$, Fig. 1. Fig. 3 is a transverse section taken at the plane of the dotted line $y\ y$, Fig. 2. Fig. 4 is a front view 20 of a header of another shape embodying my improvement, the cover being removed. Fig. 5 is a front view of a header corresponding to Fig. 1, but illustrating a modification. Fig. 6 is a vertical section of this header taken at 25 the plane of the dotted line $z\ z$, Fig. 5. Fig. 7 is a horizontal section taken at the plane of the dotted line $w\ w$, Fig. 5. Fig. 8 is a section taken at the plane of the dotted line $v\ v$, Fig. 5. Fig. 9 is a vertical section of a corner 30 portion of a header, a cover therefor, and means for securing the cover. In this view a modification is illustrated. Fig. 10 is a view corresponding to Fig. 9, but illustrating another modification. Fig. 11 is a front view 35 of a header of another form embodying the improvement. Fig. 12 is a transverse section of the header shown in Fig. 11, taken at the plane of the dotted line $u\ u$, Fig. 11. Fig. 13 is a horizontal section of this header taken at 40 the plane of the dotted line $t\ t$, Fig. 11.

Similar letters of reference designate corresponding parts in all the figures.

A designates a header. This header in all the figures, excepting only Fig. 4, is approximately of rhomboidal shape, having parallel top and bottom $a'\ a^2$, parallel inclined side portions $a^3\ a^4$, vertical side portions $a^5\ a^6$ above the inclined side portions, and vertical side portions $a^7\ a^8$ below the inclined side 50 portions. Each header has a partition a^9 . Each header is divided by said partition into two substantially triangular compartments,

here shown as communicating with each other through openings in the partition.

The form of header shown in Fig. 4 corresponds with one of the compartments of the rhomboidal header, being substantially of triangular shape. Each of the rhomboidal headers has two triangular openings a^{10} . The fronts of the headers adjacent to these openings are faced suitably to receive covers A' of triangular shape. It will be seen that the triangular openings of each of these headers are reversed, so that the apex of one will extend upwardly and a corresponding angle or corner of the other will extend downwardly. The header illustrated in Fig. 4 has one triangular opening a^{10} and one cover A' .

Tubes B are secured to the backs of the headers. These tubes will preferably be secured to the headers by being expanded into the same. It will be seen that there are six of these tubes secured to each of the rhomboidal headers and that they are so disposed as to be staggered. It will be observed that 70 three of the six are opposite each of the triangular openings of the header. The triangular header illustrated in Fig. 4 has three tubes secured to it. These tubes are disposed in the position of the apices of a triangle and are opposite the triangular opening in the front of the header.

Referring first to the example of my improvement which is illustrated in Figs. 1 to 4, inclusive, it will be seen that the inner surfaces of the sides and bottom are provided with pockets for receiving the heads of bolts C, extending through the covers A' , and provided outside the latter with nuts C' for securing them in place. The bolts C are what 85 are known as "T-bolts," having heads which, as here shown, extend transversely beyond the bodies of the bolts in two directions, and at the intermediate sides are flush with the body of the bolt. The heads may, however, 90 be of any desired shape. The pockets for these bolts consist of cavities c, having openings at the inner sides, or, in other words, toward the center of the header. These cavities are of a size to receive the heads of the 100 T-bolts. The heads of the T-bolts are capable of being slipped into these cavities if the bolts, after having their heads placed opposite the cavities, are moved laterally or to-

ward the exterior of the headers. A recess c' extends from each cavity c toward the front of the header. It will therefore be seen that the pockets are substantially of T shape. 5 The recesses c' are of a size to accommodate the portions of the bodies of the bolts which are adjacent to the heads. The cavities c extend forwardly some distance into the sides of the recesses c' behind lips or flanges c^6 . The 10 bolts may therefore be slipped sidewise into the pockets and then drawn forwardly. When drawn forwardly, they will be prevented from any lateral movement, and hence will be firmly secured in place. 15 It will be seen that the backs of the cavities c form stops c^2 , which will limit the rearward movement of the bolts. These stops are not, however, absolutely necessary. The 20 pockets on the bottoms of the headers are not shown as provided with backs; but the upper ends of nipples D, which connect one header with the header immediately above it, will serve as stops for the bolts engaged with these bottom pockets. The back of each 25 header may be strengthened by ribs c^5 , extending to those pockets which are on the sides of the headers, as shown. These ribs are, of course, only essential for strengthening the header. 30 It will be seen that I provide for fastening the covers by bolts secured to the headers a short distance rearward of the covers. I provide for securing the covers to the headers at points close to the edges of the covers, so that 35 little or no liability will be incurred of breaking the covers by applying undue force to the nuts. As the bolts are very short, owing to the fact that they are secured to the headers but a short distance from the covers, the danger 40 ordinarily arising from differential expansion and contraction in the bolts and headers is practically obviated. The bolts, when secured in the ordinary manner to the backs of the headers, are longer than the extension 45 of the sides of the headers in the direction of the length of the bolts. As wrought-iron expands and contracts more than cast-iron, much danger arises from this ordinary arrangement and use of bolts. 50 Turning now to the example of my improvement which is illustrated in Figs. 5, 6, 7, and 8, it will be seen that instead of having pockets in the headers for receiving protuberances or heads upon the bolts, I provide the 55 bolts with eyes to receive protuberances extending from the interior of the headers. It will be seen that the bolts C, which extend from the sides of the headers and partitions, are provided with eyes c , and that the sides 60 of the headers and partitions are provided with protuberances or bosses c^9 , over which the eyes of the bolts may be slipped. It will be seen that the bottoms of the headers are provided with protuberances c^4 , extending 65 around the holes in which the nipples D fit. The eyebolts which extend from the bottoms of the partitions have their eyes made large

enough to fit around these protuberances c^4 . As the eyes of these bolts, which are combined with the protuberances c^4 , fit tightly around the latter, they serve to strengthen the header in so far as they resist the breaking of the header transversely to the protuberances. The protuberances themselves tend to secure the same advantage. 75

I may provide the header with a number of lugs cast integral with it and extending inwardly from the front opening or openings. These lugs will be in the position of the bolts in the other examples of my improvement. 80 In Fig. 9 I have illustrated this modification, although I have here shown but one of the lugs. I have designated this lug by the letter c . It has a hole in it so that it forms a pocket. An ordinary bolt C has its shank 85 extended through the hole of this pocket or lug, while its head bears against the rear of the lug. The bolt extends through the cover and has a nut C' applied to it outside of the cover. 90

Instead of providing the bolt C with a head behind the lug or pocket c , I may provide the rear end of the bolt with a screw and engage the screw with a female screw-thread in the lug or pocket, as illustrated in Fig. 10. The 95 bolt will extend through the cover and have a nut applied to the outer end.

In Figs. 11, 12, and 13 I have shown a long rectangular header provided with removable covers extending across openings, each of 100 which is located opposite the ends of two tubes B. Bolts C are secured to these headers. These bolts are secured to pockets corresponding exactly with the pockets shown in Figs. 1, 2, 3, and 4. Obviously the bolts which I 105 have described might be hinged to the side walls of the headers and occupy the same positions as they occupy in the examples of my improvement in which they have been illustrated. 110

The same advantages inure in this example of my improvement as in the other.

In order to obviate the necessity for frequently removing the covers of the headers I provide said covers with an observation-hole d , or a number of such holes. As shown, each observation-hole is located opposite one of the water-tubes. It has fitted to it a removable stopper d' . In the present instance this stopper is made in the form of a screw-threaded 115 plug having a flange at the base of the head. The body of the plug engages with a screw-thread in the interior of the hole. The flange enters a recess at the outer end of the hole and fits against a packing d^2 in the back of the recess. The cover may be of other form. 120

A single observation-hole for each cover may be sufficient when located at the apex of a triangular cover applied to headers such as I have described. The observation-hole of 130 one cover will be opposite a tube in one row and the observation-hole of the next cover will be opposite a tube in another row.

Although the observation-holes will not af-

ford an opportunity for inspecting all the tubes, yet they will provide for an inspection of tubes in the several rows, and as the condition of all the tubes is usually the same an 5 inspection of certain tubes will be sufficient to determine the condition of all.

The opportunity afforded by the observation-holes for ascertaining the condition of the water-tubes obviates the necessity for frequently removing the covers of the headers, and this is advantageous, because when the covers are taken off and reapplied it is not easy to reapply them in exactly the same condition that they were before removal.

15 Of course my improvement in securing the covers of the headers and in affording an opportunity for inspecting the tubes is not restricted to the precise forms of headers which I have illustrated, but are applicable to various forms of headers in use.

What I claim as my invention, and desire to secure by Letters Patent, is—

1. The combination, with a header and a cover therefor, of a number of short bolts having their heads engaging with pockets on the inner side walls near the front of the header, and said bolts extending from the interior of the header through the cover at points adjacent to its edge, substantially as specified.

2. The combination, with a header and a cover therefor, of bolts extending from the in-

terior of the header through the cover, the bolts having heads and the interior of the sides of the header being provided with pockets, whereby they are detachably secured together, and stops in the rear of said pockets, substantially as specified.

3. The combination, with a header and a cover therefor, of bolts extending from the interior of the header through the cover, said bolts having their heads engaging with the inner side wall of the header, whereby the bolts and header are detachably secured together, and strengthening-ribs in the header extending between the points where the bolt heads are attached to the header, substantially as specified.

4. The combination, with a header and a cover therefor, of an observation-hole in the cover of less diameter than the tubes, and an outwardly - removable threaded stopper for said hole, substantially as specified.

5. The combination, with a header and a cover therefor, of bolts securing the header in place, and pockets located upon the sides of the header, consisting of cavities c , recesses c' , flanges c'' , and stops c^3 , substantially as specified.

WILLIAM E. KELLY.
